UNITED STATES PATENT OFFICE.

JAMES BROWN, OF PHILADELPHIA, PENNSYLVANIA, ASSIGNOR TO VENANGO KNITTING MILLS, INCORPORATED, OF PHILADELPHIA, PENNSYLVANIA, A CORPORATION OF PENNSYLVANIA.

TENSION DEVICE FOR CIRCULAR-KNITTING MACHINES.

1,255,815.

Specification of Letters Patent.

Patented Feb. 5, 1918.

Application filed January 25, 1917. Serial No. 144,504.

To all whom it may concern:

Be it known that I, JAMES BROWN, a citizen of the United States, and a resident of Philadelphia, county of Philadelphia, and

5 State of Pennsylvania, have invented a certain new and useful Improved Tension Device for Circular-Knitting Machines, of which the following is a specification.

This invention has relation to circular 10 knitting machines and has more particular relation to an extra tension device therefor for placing additional tension upon yarn when a yarn lever is being put out of action.

Difficulty has been experienced in practice 15 when shifting yarn levers out of action because of the fact that the ordinary tension devices as used upon knitting machines fail to maintain the yarn in proper relation with respect to the thread clamp or binder and cutter to insure the yarn being guided accurately beneath the thread, clamp or binder 20 and between the cutter-blades.

The principal object of the present invention is to overcome the above described 25 disadvantageous features and provide a simple, efficient, reliable and comparatively inexpensive device for placing extra tension upon yarns during yarn-lever shifting periods. Other and further objects reside in the provision of details of construction as will hereinafter more fully appear.

The invention consists of the improvements hereinafter described and finally claimed.

35 The nature, characteristic features and scope of the invention will be more fully understood from the following description taken in connection with the accompanying drawings forming part hereof and in which:

40 Figure 1 is a top or plan view of sufficient knitting machine structure to illustrate the application thereto of the tension device of the invention;

Fig. 2 is a view in section thereof, and

45 Fig. 3 is a perspective view of the tension device.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously

arranged and organized and that my invention is not limited to the precise arrangement and organization of the instrumentalities as herein shown and described.

In the drawings 10 designates a ring-like structure provided with a yarn-lever support 11 provided with yarn-levers 12. Mounted in operative position with respect to said

ring are needles 13. Also mounted upon the ring 10 is a support 14 which extends within the ring and has operatively positioned 65 thereon a yarn clamp or binder 15 and a yarn cutter 16. The above described parts are of well known construction and I do not claim the same as part of the present invention except in so far as these parts are associated with my tension device to provide a novel and operative combination. The tension device of the invention is designated A and is positioned as near to the yarn-levers 70 12 as possible in order to obtain best results. 75

That is, the device should be positioned immediately above the yarn levers so that the yarn may be guided, without strain, to said device. This device embraces an angular member consisting of a transverse support or 80 foot portion 17 terminating in a longitudinal extension 18 disposed at right angles thereto and extended upwardly and outwardly at an inclination, the parts being preferably formed integral with one another. The foot 85 portion is provided with a transverse, elongated slot 19 and is secured to the support 11 by means of a screw 20. By reason of said slot the device may be adjusted laterally of the support 11 so that the device as a whole 90 may be shifted to a position immediately above the yarn levers. As thus positioned, as is clearly illustrated in Fig. 2, the device A is located immediately above the yarn-levers 12 and below the yarn guide 21. Upon each 95 side of the extension 18 and at the free end thereof is a notched portion 21, see Fig. 3, the purpose of which will presently appear.

Also located upon each side of the extension 18 and secured thereto at said free end by 100 means of a screw 22 and nut 23, is a member 24 of spring metal the free ends 25 of which are outwardly flared as clearly shown in Fig. 3. These free ends 25 terminate at a point immediately adjacent the upwardly curved 105 part of the extension which joins the foot to the extension proper.

A description will now be given of the

mode of operation of the combination of parts as above set forth.

In practice it may be necessary to change the color of yarn employed or change the character of yarn, that is the weight, thickness or quality. For illustrative purposes let it be assumed that knitting requiring several colors of yarn is taking place. Let it be further assumed that white and blue yarn 10 is to be employed in such knitting. As an illustration, knitting is taking place with white yarn, designated *a*, which yarn passes through yarn guide 21 to and through yarn lever which is in lowered or operative position and thence to the needles 13. It will be observed in this connection that said white yarn *a* is running free between the extension 18 and the flared end 25 of the spring member 24. It will also be understood 15 that the ordinary yarn tension device (not shown) is employed as usual. Let it be assumed now that it be desired to knit with blue yarn, designated *b*. The yarn lever 12' (blue yarn) is now lowered to working 20 position approximately at the same time the yarn lever 12 (white yarn) is raised. With the lowering of the lever 12' the yarn is caused to pass forward between the extension 18 and the spring member 24' away 25 from the flared end thereof, thus putting extra tension upon the yarn. The blue yarn meanwhile by the lifting of the lever 12' is caused to move outward and run free between the extension 18 and the free end of spring member 24'. With the placing of 30 extra tension upon the white yarn *a*, no yarn is picked down by the needles so that by the time the needle which in its regular travel was the last to pick down yarn reaches first 35 the clamp or binder and then the cutter, said needle has caused yarn to pass beneath the binder 15 which is freely movable under spring tension and between the blades of the cutter 16. Meanwhile, it will be understood 40 that the yarn *b* (blue) which previously had been held by binder is being picked up by the needles and knitting with blue yarn is under way, it being understood that such yarn *b* is running free under flaring end 25 of spring member 12'. With the feeding of 45 white yarn to the binder and cutter well known mechanism has operated the cutter 16 to sever the same, the binder of course maintaining the yarn in proper position and the 50 yarn lever 12 being raised said yarn is maintained under tension. It will of course be understood that all of the above operations are timed to coact at the proper moment and which operating mechanism forms no part 55 of the present invention. When yarn *a* is again required for knitting purposes, the above operation is repeated to put out of action the blue yarn lever and throw into action the white yarn lever as will be readily understood without further description.

As the yarn passes between the spring member 24-24' and the extension 18 lint and the like is deposited therebetween which requires frequent removal in order that the said springs may be close to said extension. 70 In order that such dirt may be readily cleaned from the device, a suitable tool may be inserted in an aperture 21, before described, and moved between a spring and the extension and toward the foot 17. 75

It will now be apparent that I have devised a novel and useful construction which embodies the features of advantage enumerated as desirable in the statement of the invention and the above description and 80 while I have in the present instance shown and described the preferred embodiment thereof which has been found in practice to give satisfactory and reliable results, it is to be understood that the same is susceptible 85 of modification in various particulars without departing from the spirit or scope of the invention or sacrificing any of its advantages.

What I claim is:

1. A device of the character stated comprising a transversely disposed support having a similarly disposed slot therethrough to accommodate means for effecting lateral adjustment of the device, a longitudinally extended member projected from said support and a leaf spring fixed to the free end of said member upon each side thereof and disposed in substantially abutting, parallel relation therewith throughout the major portion 100 of its extent.

2. A device of the character stated comprising a transversely disposed support having a similarly disposed slot therethrough to accommodate means for effecting lateral adjustment of the device, a member projected from said support in an upwardly and longitudinally extended manner and a leaf spring secured to the free end of said member upon each side thereof in parallelism 110 therewith, the free ends of said springs being flared.

3. A device of the character stated comprising a transversely disposed support having a similarly disposed slot therethrough to 115 accommodate means for effecting lateral adjustment of the device, an upwardly and longitudinally extended member projected from said support and a leaf spring secured to the free end of said member upon each 120 side thereof, each spring being in substantially abutting parallel relation with said member throughout the major portion of its extent, the free ends of said springs being flared.

4. A device of the character stated comprising a transversely disposed support having a similarly disposed slot therethrough to accommodate means for effecting lateral adjustment of the device, an upwardly and 130

longitudinally extended member projected from said support, the opposite sides of which member are notched adjacent the free end thereof and a leaf spring rigidly secured to said free end of said member and beyond said notches upon each side of said member, each spring being in substantially abutting, parallel relation with said member throughout the major portion of its ex-

tent, the free ends of said springs being 10 flared.

In testimony whereof, I have hereunto signed my name.

JAMES BROWN.
